UNITED STATES PATENT OFFICE.

CHARLES J. AHRENFELDT, OF NEW YORK, N. Y.

DESIGN FOR A PLATE.

SPECIFICATION forming part of Design No. 29,169, dated August 9, 1898.

Application filed February 9, 1898. Serial No. 669,724. Term of patent 7 years.

To all whom it may concern:

Be it known that I, CHARLES J. AHRENFELDT, a citizen of the United States, residing at the city of New York, in the county 5 and State of New York, have invented and produced a new and original Design for a Plate, of which the following is a specification.

My design consists of a plate having the shape and ornamentation hereinafter described, reference being had herein to the accompanying drawings, forming a part hereof, in which like letters of reference refer to like parts in each figure.

In the said drawings, Figure 1 is a top plan 15 view of a plate embodying my design. Fig. 2 is a medial cross-section of the same, taken on the line 2 2 of Fig. 1.

The outer flange A² of the plate A is multifoil in form, indentations B in its periphery 20 leading to radial depressions B', extending to the bevel A' in the interior of the plate. Between this inner bevel A' and the periphery, parallel thereto, is an annular band of latticed ornament C, having small circles c 25 at the points of intersection and the angles

of the lines of lattice-work and being bordered on either side by parallel scrolls D, having volute terminals d and a fin-like projection d' on the inner side near the said terminals. At the intervals between the scrolls 30 D the lines of the latticed ornamentation project beyond the scrolls and terminate at the edge of the bevel A' on the inner side at the said intervals. Directly between the intervals of the scrolls D and the indentations B 35 on the lines of depression B' is a cruciate leaf ornament E and on either side of the same two foliate ornaments and a scroll F, curved in the opposite direction from the scroll D and having a volute terminal f. 40

What I claim is—

The design for a plate herein shown and described.

In witness whereof I have hereunto affixed my signature, in the presence of two witnesses, 45 at the city of New York.

CHARLES J. AHRENFELDT.

Witnesses:

W. A. WHEELER,
M. V. DUERING.
